UNITED STATES PATENT OFFICE

CARL T. SWENSON, OF MILWAUKEE, WISCONSIN, ASSIGNOR TO MILWAUKEE SADDLERY COMPANY, OF MILWAUKEE, WISCONSIN, A CORPORATION OF WISCONSIN

KNEE PROTECTOR

Application filed April 6, 1928. Serial No. 287,884.

The invention relates to clothing and more particularly to a knee protector.

The washing and scrubbing of floors and other work done in a kneeling position are arduous tasks. Floors are hard and sometimes rough and uneven and the weight of the body in scrubbing and some other kinds of work is carried principally on the knees. The object of this invention is to provide a knee protector for use in work requiring a kneeling position that will lighten the burden of such work and which may be readily placed on or removed from the wearer; will keep the wearer's knees dry; will cushion the knees; and will withstand rough usage.

The invention further consists in the several features hereinafter set forth and more particularly defined by claims at the conclusion hereof.

20 In the drawings, Fig. 1 is a side elevation view of a knee protector embodying the invention, shown applied to the wearer;

Fig. 2 is a perspective view of said protector;

25 Fig. 3 is a section taken on the line 3—3 of Fig. 2;

Fig. 4 is a section taken on the line 4—4 of Fig. 2;

Fig. 5 is a detail section, similar to Fig. 30 4, showing a certain modification.

Referring to the drawings the knee protector includes a front facing piece 6 of heavy, flexible material, preferably waterproof material, such as a suitable leather or canvas, 35 and 7 a pad of cushioning material, such as felt, rubber or other suitable material, and preferably a pad of sponge rubber.

The pad 7 is secured to the facing 6 by stitching the same adjacent the edges of said pad 40 by rows of stitching 8, 9, 10 and 11, the facing either being folded over at its side edges, as shown in Figs. 2 and 4, or a binding strip 12 being stitched to the facing and pad to form a folded-over edge, as shown in Fig. 5, 45 the end portions 13 of the folded-over por-

tion also extending inwardly and held down against the pad by the stitching 9 and 11 to distribute the strain in an efficient manner and so that the fasteners hereinafter described pull on this extended edge.

The top and bottom portions 14 and 15 of the facing extend beyond the rubber pad and have rubber fabric bands or webbing 16 secured thereto by stitching 17, these bands being secured while said webbing is under tension so that the facing will not interfere with the stretching of the bands while in use. This elastic material may be of any desired width and its ends are equipped with detachable fasteners, one of which at each end, is adjustable. As shown, one end of the band has a shouldered stud 18 secured thereto and the other end has an eyed member 19 mounted in a loop whose length may be adjusted by adjusting a three-bar fitting 20 along the band.

60 The stitching 9 and 11 is preferably in a circular arc so that when the device is in use it will readily conform to the leg of the wearer.

65 The device may be readily applied to the wearer by connecting the ends of the bands together above and below the knee, as shown in Fig. 1, and the wearer's knees thus rest on the sponge rubber cushion, out of the water in the case of washing and scrubbing, and the outer facing protects the cushion and provides a good mounting for the pad and the fastening means.

70 I desire it to be understood that this invention is not to be limited to any particular form or arrangement of parts except insofar as such limitations are specified in the claims.

75 What I claim as my invention is:

1. In a knee protector, the combination of 80 a front facing, a cushioning pad secured to said facing, said facing having top and bottom portions extending beyond said pad, bands of elastic material having tensioned connection with the extended top and bottom 85 portions of said front facing and detachable 90

fasteners for securing together the ends of each band.

2. In a knee protector, the combination of a front facing of flexible, waterproof material, a sponge rubber pad secured to the back of said facing, said facing having top and bottom portions extending beyond said pad, bands of elastic material having tensioned connection with the extended top and bottom portions of said facing, and detachable fasteners for securing together the ends of each band.

In testimony whereof, I affix my signature.
CARL T. SWENSON.
